UNITED STATES PATENT OFFICE.

THOMAS H. COLE, OF EAST ALBANY, AND CHARLES McCARRICK, OF TIVOLI, NEW YORK.

COMBINATION-LOCK.

SPECIFICATION forming part of Letters Patent No. 325,321, dated September 1, 1885.

Application filed August 23, 1884. (Model.)

To all whom it may concern

Be it known that we, THOMAS HENRY COLE, of East Albany, in the county of Rensselaer and State of New York, and CHARLES McCARRICK, of Tivoli, in the county of Dutchess and State of New York, have invented certain new and useful Improvements in Combination-Locks, of which the following is a full, clear, and exact description.

10 This invention relates to an improved combination hasp-lock.

The invention consists of the construction, arrangement, and combination of parts, all as hereinafter described and claimed.

15 Reference is to be had to the accompanying drawings, forming part of this specification, in which similar letters of reference indicate corresponding parts in all the figures.

Figure 1 is a front elevation of our new and 20 improved combination-lock. Fig. 2 is an inverted plan view of the lock, the back plate, G, being removed. Fig. 3 is a sectional elevation of the lock taken on line $\alpha\alpha$ of Fig. 2. Figs. 4 and 5 show the form of the sliding tumblers. Figs. 6 and 7 show the division- 25 plates for the tumblers, and Fig. 8 shows the plate for operating the sliding tumblers and the bolt of the lock.

20 A represents the lock-box. B represents the sliding bolt. C C' represent the sliding tumblers, in this instance two in number, and D represents two division-plates for separating the sliding tumblers C C', and E represents the operating-plate for operating the 35 sliding tumblers C C' and the bolt B.

The box A has the bolt a fitted in it, which is provided at its outer end with the knobbed disk F, and at its inner end with the pinion b, which meshes with the teeth c, formed at one 40 edge of the operating-plate E, so that by turning the disk F the pinion b will cause the plate E to be moved backward or forward in the box A. Upon its inside the box A is formed with the lugs d d, which serve, in connection with one of the outer walls of the box, to keep the sliding tumblers C C' and the division-plates D and operating-plate E in place. The box A is also formed upon the inside with the stop-lug d' and with the side lugs, e e, upon 45 which one end of the back plate, G, is secured by suitable screws, passing through the cor-

ners of the plate and entering screw-threaded recesses made in the lugs, the other end of the back plate, G, being held by a single screw, passing through the plate and entering the screw-threaded opening e'. The lug d' serves as a stop or lock for the bolt B to prevent it from backward movement when it is shoved forward and outward to a locked position (the position shown in Fig. 3) by the sliding plate E. The lugs e e are formed a short distance from the outer end wall, a', of the box A, so as to form the space f, which receives the staple J, so that the staple, when the lock is applied to it, will be entirely inclosed by the 55 lock-box A. The lugs e e also serve as guides to the forward end of the bolt B in its backward and forward movement, as will be understood from Fig. 2.

The bolt B in this instance is formed with 70 the lug g, and by the action of the spring h, placed in a recess, h', made in the back of said bolt, so as to act against the side wall, a', of the box A, the lug g will be constantly held pressed against the edges of the sliding tumblers and the edge of the operating-plate E.

The operating-plate E is provided with the pin i, and is formed with the notch j, the pin being for the purpose of sliding the tumblers C C', and the notch for receiving the lug g of 80 the bolt B, for sliding the said bolt. The notch j is inclined at one end, as shown at k, for shifting the lug g of the bolt B out of the notch j, and for bringing the rear end of the bolt B in line with the lug d', as hereinafter 85 described.

The division-plates D are for the purpose of separating the tumblers C C' from each other, and for separating the lower tumbler, C', from the operating-plate E, so that this plate and 90 the tumblers may slide independently of each other, except as the tumblers are moved by the pin i of the plate E.

The division-plates D may be of any suitable form, and duplicates of each other. In this 95 instance they are each cut away at l to form a clearance for the pin i, and at l', so as not to interfere with the movement of the lug g of the bolt B, and they are each cut away to form the shoulders l', which embrace the lugs d, as 100 shown in Fig. 2, so that they cannot move out of place.

5 The sliding tumbler C is made of a rectangular piece of sheet metal, notched at m, to receive the lug g, and again at m', to form the shoulders m², against which the pin i is adapted to strike for moving the tumbler longitudinally. The notch m is made out of line with the center of the tumbler C, so that by reversing the tumbler in the lock-box A—that is, by turning it end for end and inverting it—the combination of the lock will be changed.

10 The tumbler C' is like the tumbler C, being cut away at n, and also cut away at its side edges at n', except that these notches are arranged differently with reference to the transverse center of the tumbler—that is, they are made on the opposite side of said center—so that by interchanging the tumbler C' with the tumbler C the combination will be changed, and so also by reversing this tumbler end for 15 end (the tumbler C remaining the same) the combination will be changed.

15 The outer surface of the disk F is graduated, as shown at o, Fig. 1, and the box A has the index-mark o' formed upon it for indicating 20 the combination of the lock.

25 Beneath the back plate, G, is placed the flat curved spring p, which bears upon the upper tumbler, C, and serves to hold the tumblers and the division-plates in place in the box A.

30 The bolt B being shoved forward to locked position—the position shown in full lines in Fig. 3—in order to withdraw the bolt the tumblers C C' must be moved so that the notches m n in the edges of the tumblers toward the 35 bolt B will stand exactly in line with the lug g of the bolt B, and the plate E must be moved to such position that the notch j thereof will also stand in line with the said lug g. The tumblers and plate G being in this position, 40 the spring h will act to force the bolt B to the position shown in dotted lines in Fig. 2; the lug g of the bolt entering the notches m, n, and j, and this movement of the bolt B, caused by the spring h, is sufficient to carry the rear 45 end of the bolt B out of line with the stud d', so that by simply turning disk F by the knob f' thereof the notch j in the operating-plate E, acting against the stud g, will slide the bolt B backward and withdraw it from the staple J.

50 To force the bolt B forward again to lock it with the staple J, it is only necessary to turn the disk F in the opposite direction, which will cause the beveled end k of the notch j, acting against the lug g, to move the bolt B 55 longitudinally toward the staple J until the rear end of the bolt passes the stud d', whereupon the bevel k, acting as a cam, will move the bolt B outward, so that its rear end will stand in front of the lug d', as shown in full 60 lines in Fig. 2. The bolt B being thus moved outward by the bevel k, the operating-plate E will move independently of the bolt B, so that the said plate may be moved past the lug g in either direction, which will cause the 65 pin i to move the tumblers C C', and thus disturb the coincidence of the notches m, n, and j and bring the edges of the tumblers C C' and

the plate E all abreast of the lug g of the bolt B, which will hold the bolt B in line with the lug d', so that the bolt B cannot in any manner be withdrawn until the notches m, n, and j are all brought again in line with each other and with the lug g of the bolt.

70 In order to bring the notches m, n, and j into line with each other and with lug g, the disk F must be turned to right and left with a regular combination of movements, and this combination must be known so that with the aid of the graduation-marks o and the index o' the exact required movements of the disk 80 F may be effected.

85 In order to learn the combination necessary to operate the lock, the back plate, G, must be removed, and the movement of the tumblers C C' and plate E observed. To ascertain the combination (the plate G being removed) the disk F will first be turned to move the plate E as far in the direction of the arrow in Fig. 3 as it will go. Then the disk F must be turned in the opposite direction until the tumbler C is moved by pin i, so that the notch m stands just in line with the lug g of the bolt B, the position of the index o' on the graduation o being carefully noted. The disk F will then again be reversed or 95 turned in the opposite direction until the notch of the tumbler C' is moved by the pin i so that the notch n stands exactly in line with the lug g, the position of the index o being again carefully noted, as before. Then, 100 finally, the disk F will be again reversed and turned until the notch j of the operating-plate E stands exactly in line with the lug g, noting as before the position of the index o'. In this position the spring h will force the 105 bolt B forward, as above stated, the lug g entering the notches m n j.

110 As above stated, by changing the tumblers C C' the combination will be changed so that with each change of the tumblers the above method must be pursued to learn the combination, which must be strictly followed to open the lock. The combination may also be changed by moving the pin i to different positions in the holes i' in the plate E, thus enabling an indefinite number of changes of combination to be made.

115 We do not confine ourselves to the use of two sliding tumblers, as any suitable number might be used, greatly complicating the lock; nor do we confine ourselves to the "hasp" form of lock shown, as the principle of the lock is applicable to locks of various forms, to be used for various purposes.

Having thus described our invention, what 125 we claim as new, and desire to secure by Letters Patent, is—

1. The box A, formed or provided with the lug d', the bolt B, formed or provided with the lug g, and the spring h, adapted to press the bolt inward in the box, in combination with the tumblers C C', plate E, provided with a pin for operating the tumblers, and notched at its edge to receive the lug g of bolt B for

- moving the bolt longitudinally, division-plates between the tumblers and plate E, and means for operating the plate E, substantially as set forth.
- 5 2. The box A, formed or provided with the stop-lug *d'*, and the bolt B, formed or provided with the lug *g*, placed in the box A and pressed inward by the spring *h*, in combination with the notched tumblers C C', division-plates D, and operating-plate E, provided with pin *i*, for operating the tumblers, and notched at its edge with the beveled notch *j k* for receiving the lug *g* and moving the bolt B both longitudinally and laterally, the plate E being 10 formed with the rack *c* to receive the pinion *b* on bolt *a*, substantially as and for the purposes described.
3. In a combination-lock, the lock-box A, the sliding tumblers C C', separate division-plates D, and operating-plate E, held in place 20 in the box A of the lock by the removable back plate, means for operating said plate E, spring *p*, and lugs *d d*, formed in the box A, substantially as described.
